Primary Examiner — Deanna L Pratt(74) *Attorney, Agent, or Firm* — Lewis Roca Rothgerber Christie LLP(57) **CLAIM**

The ornamental design for sectional, as shown and described.

DESCRIPTION

FIG. 1 is a front and right side perspective view of a sectional showing my new design in a first configuration; FIG. 2 is a front elevation view thereof; FIG. 3 is a right side elevation view thereof, the left side being a mirror image; FIG. 4 is a top plan view thereof; FIG. 5 is a rear view thereof; FIG. 6 is a close-up view of the weave pattern on the sectional; FIG. 7 is a front and left side perspective view of a sectional showing my new design in a second configuration; FIG. 8 is a front elevation view thereof; FIG. 9 is a right side elevation view thereof; FIG. 10 is a top plan view thereof; and, FIG. 11 is a rear view thereof.

The broken lines show environmental subject matter and form no part of the claimed design. The woven pattern partially shown on the sides, top, front and back of the sectional in FIG. 1-11 is continuous throughout.
